UNITED STATES PATENT OFFICE.

CATHERINE BRADLEY AND LILLIAN MARGHERITTA BRADLEY, OF BATHURST, NEW BRUNSWICK, CANADA.

WAXED MILK-BOTTLE STOPPER MADE OF PASTEBOARD.

Application filed April 22, 1926, Serial No. 103,948, and in Canada September 21, 1925.

Our invention is a pasteboard milk bottle stopper constructed in such a way as to enable the stopper to be removed by the thumb and finger without the thumb or 5 finger coming in contact in any way with the milk. Thus it is perfectly sanitary. It also eliminates the spilling of milk as is usually the case when a stopper is removed by means of plunging stopper down 10 into the bottle on one end to grasp the other end. It does away with the use of a knife or other article in removing. As the tongue is threaded from the centre of stopper, the pull is chiefly at the centre. 15 Thus the danger of tearing, when removing stopper, is avoided. The fact that the tongue or lifter is brought up thru the stopper, prevents it interfering with the edge. The slits being of the same size 20 (length) as distance across the tongue or lifter, there is no chance of air getting in. When the stopper is placed in the bottle, the little tongue or lifter because it extends beyond the edge of stopper, will there- 25 fore remain up resting on the edge of mouth of bottle. Then it is easy to grasp tongue with thumb and finger, give it a little pull and the stopper is out.

We attain these objects by the mechanism

illustrated in the accompanying drawings 30 in which—

Fig. 1 shows the circular pasteboard with slits or cuts.

Fig. 2 shows the tongue or lifter.

Fig. 3 is the finished stopper (with tongue 35 threaded thru it).

Referring to the drawings:—1 represents the flat circular stopper, having the two cuts or slits 2 and 3. The tongue 5 is threaded thru slits 2 and 3 as follows:—Upper 40 end 6 of the tongue is inserted down thru slit 2 in stopper. Then same end 6 is brought up again thru slit 3. This leaves cross section 4 and upper end 6 showing on top side of stopper. Upper end 6 45 projects a little beyond edge of stopper.

What we claim as our invention and desire to secure by Letters Patent is:—

A new and useful closure for a bottle or jar consisting of a disc showing two 50 slots, one thru centre, the other near the edge and parallel to first slot, and a tongue detachably secured to disc by a necessarily larger portion at one end, the other end thereof being passed thru said slots to form 55 an extractor pad or tab.
